Primary Examiner — Dana K Weiland(74) *Attorney, Agent, or Firm* — Cantor Colburn LLP(57) **CLAIM**

The ornamental design for an electronic device, as shown and described.

DESCRIPTION

FIG. 1 is a front perspective view of an electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the portion 9 in FIG. 1;

FIG. 10 is an enlarged view of the portion 10 in FIG. 1;

FIG. 11 is an enlarged view of the portion 11 in FIG. 3;

FIG. 12 is an enlarged view of the portion 12 in FIG. 8;

FIG. 13 is another front perspective view of the electronic device in which the display screen is extended.

FIG. 14 is a rear perspective view of the electronic device in which the display screen is extended.

FIG. 15 is an enlarged view of the portion 15 in FIG. 13;

FIG. 16 is an enlarged view of the portion 16 in FIG. 13; and,

FIG. 17 is an enlarged view of the portion 17 in FIG. 14. The broken lines illustrating portions of the electronic device form no part of the claimed design. The dot-dash broken lines in the figures represent a boundary line and form no part of the claimed design. The dot-dot-dash broken lines surrounding portions of the claimed design that are illustrated in enlargements form no part of the claimed design.
